UNITED STATES PATENT OFFICE.

JOSEPH P. GIBSON, OF SPRING VALLEY, ILLINOIS.

DRAWER-LOCKING DEVICE FOR TRUNKS.

Application filed July 19, 1922. Serial No. 576,070.

To all whom it may concern:

Be it known that I, JOSEPH P. GIBSON, a citizen of the United States, residing at Spring Valley, in the county of Bureau and 5 State of Illinois, have invented certain new and useful Improvements in Drawer-Locking Devices for Trunks, of which the following is a specification, reference being had to the accompanying drawings.

10 This invention relates to drawer locking means and more particularly to drawer locking means for trunks.

An object of the invention is to provide means of this character capable of locking 15 the drawers of a wardrobe trunk by means lockingly engaged with the section of the trunk in which the drawers are disposed.

It is another object of the invention to provide means of this character including 20 a holding member adapted to engage the drawers of a trunk, said member being provided with means for locking engagement with one edge portion of the casing in which the drawers are disposed.

25 It is a further object of the invention to provide locking means of this character embodying a holding bar capable of being locked to the outer face of the trunk section without requiring alteration of the drawers 30 or the trunk.

With these and other objects in view, the invention consists in the improved construction and arrangement of parts to be herein-after more particularly described, fully 35 claimed and illustrated in the accompanying drawings, in which:—

Figure 1 is a view in elevation of a wardrobe trunk showing the invention applied;

40 Figure 2 is a fragmentary longitudinal sectional view of the drawer section of the trunk showing the invention applied;

Figure 3 is a perspective view of the locking bar; and

45 Figure 4 is a perspective view of the truss, a portion of the socket keeper being broken away to show the socket for the reception of the keeper.

Referring to the drawings, 5 designates a trunk including sections 6 and 7, the section 50 7 being provided with a tier of drawers 8, each drawer being provided with a handle 9. Carried by the section 7, adjacent one end thereof is a support 10 from the central portion of which a keeper 11 projects, said 55 keeper having an opening 12, the purpose of which will be hereinafter described.

The upper end 13 of the section 7 is bulged in a manner common to wardrobe trunks. Said end is formed through the provision of a truss 14 which is disposed upon the outer face of the end wall of the section 7. In the present invention the truss is utilized also as a support for a portion of the locking mechanism. This is possible by the provision of a socket 15 in the central portion of the outer face of the truss, said socket being adapted to receive a socket lock keeper 16. The socket portion of the keeper extends into the socket 15, while the flange 17 of the keeper engages the outer face of the truss 14. Rivets 18 are used to fasten the keeper to the truss. These rivets are arranged to extend laterally of the truss so as to render prying of the keeper from the truss impossible. By this means the keeper 15 is disposed substantially flush with the outer face of the truss and the edge of the end portion 13 of the trunk section 7. The object is to render the device as compact as possible and prevent interference with the closing 80 of the sections. A holding bar 19 is provided, said bar being constructed of substantial material and having its end portion 20 slightly curved longitudinally, the extremity of said end portion being beveled 85 and rounded to permit ready insertion of the holder in the slots 12 of the keeper 11. The opposite end portion 21 of the bar is provided with an opening 22. A lock 23 is 90 provided, said lock being of the trunk type, that is, with a rotatable lock bolt or double spring pressed locking bolt, in other words, a lock of a type to permit the bar to be locked to the outer face of the truss, without requiring the lock to extend beneath the 95 truss or between the truss and the drawer. The lock comprises a body member including an extension 24, said extension being reduced to provide a shoulder 25. The extension is also provided with an opening 26 100 adapted to register with the opening 22 of the bar 19. When the lock is applied, the extremity of the end portion 21 of the bar is adapted to engage the shoulder 25, so as to prevent movement of the body member of the lock laterally of the bar, a rivet 27 being used to secure the extension 24 to the bar. By this means the locking mechanism of the lock 23 projects a slight distance beyond the 105 side face of the bar. To facilitate application of the bar, a ring 28 is connected to the bar adjacent the body member of the lock.

110

In the application of the lock, the end portion 20 of the bar is passed through the handle member 9 of each drawer of the tier and through the keeper 11. The end portion 5 21 is then moved toward the keeper 16, the locking mechanism being inserted in the keeper so as to dispose the body member of the lock and the bar in parallel relation to the outer face of the truss 14. The lock is 10 then operated to lock the bar through the section 7.

An important feature of this lock is that it is not necessary to extend the body of the lock, the bolt of the lock, or any portion of 15 the locking means beneath the truss, or inwardly of the end wall of the section 7. It is not necessary to extend the lock within the top drawer or to connect the lock or locking bar in any manner to the top drawer. This 20 permits the top drawer, as well as the middle drawers, to be embraced by a substantial member extending over the truss and the outer face of the top drawer. In addition to this the locking mechanism is rendered 25 compact, so that it may be disposed between the sections when in their closed positions without interfering with the locking of the trunk. Another advantage of this arrangement is that the locking means is disposed 30 directly beneath the valance A of the trunk structure so that the lock is protected by the

valance and the insertion of a tool beneath the lock or keeper being prevented by the protecting portions of the valance. With this novel form of lock it is only necessary 35 to provide a recess in the truss or edge of the bowed end of the trunk section and apply the keeper 11. The rest of the locking mechanism is carried by the holding bar 19.

What is claimed is:—

In combination with a truss for bulging the end wall of a wardrobe trunk section, the truss having its upper face longitudinally curved and having a socket in the outer side face thereof, said outer face being disposed flush with the outer walls of the drawers of said trunk section, a socket lock keeper disposed in the recess of the truss, and having ears engaged with and secured to the outer face of the truss, inwardly of the longitudinal edges of said truss, and a holding bar arranged to engage the drawers, a trunk lock secured to one end of the bar and extending beyond said end, the body portion of said lock being disposed parallel to the outer face of the truss and the outer walls of the drawers, the locking mechanism of said lock being adapted to enter the socket lock keeper.

In testimony whereof I hereunto affix my 60 signature.

JOSEPH P. GIBSON.
